UNITED STATES PATENT OFFICE.

CLIFTON L. ANWAY, OF PARSONS, KANSAS.

AIRSHIP.

982,561.

Specification of Letters Patent. Patented Jan. 24, 1911.

Application filed October 27, 1909. Serial No. 524,850.

To all whom it may concern:

Be it known that I, CLIFTON L. ANWAY, a citizen of the United States, residing at Parsons, in the county of Labette and State of 5 Kansas, have invented new and useful Improvements in Airships, of which the following is a specification.

This invention relates to air ships and the object in view is to provide a practical air 10 ship of the combined type of rigid gas inflated, dirigible and aeroplane combined with suitable propelling and controlling or steering mechanism whereby the machine as a whole is rendered comparatively buoyant 15 in air and capable of being easily and accurately controlled under all the operations necessary in the careful and proper manipulation of air craft.

With the above general object in view, the 20 invention consists in the novel construction, combination and arrangement of parts hereinafter fully described, illustrated and claimed.

In the accompanying drawings:—Figure 25 1 is a plan view of an air ship embodying the present invention. Fig. 2 is a side elevation of the same. Fig. 3 is a front elevation of the machine. Fig. 4 is a horizontal longitudinal section taken about centrally 30 of the machine. Fig. 5 is a vertical longitudinal section taken on the line 5—5 of Fig. 4. Fig. 6 is a vertical cross section on the line 6—6 of Fig. 4. Fig. 7 is another vertical cross section taken on the line 7—7 of 35 Fig. 4. Fig. 8 is a vertical cross section through the machine taken on the line 8—8 of Fig. 4. Fig. 9 is a vertical cross section taken on the line 9—9 of Fig. 5.

It will be observed by reference to the 40 plan view of Fig. 1 that I employ an elongated or cigar shaped body 1 which is shown in Figs. 4 and 5 comprises a central longitudinal air flume or passage 2 giving an unobstructed passage way for the air through 45 the body of the machine and along the longitudinal axis thereof. Above and below the central air passage 2, the shell or body 1 of the machine is divided off by means of 50 partitions 3 into any desired number of separate or independent gas chambers 4 each of which is therefore designed to hold an independent supply of hydrogen gas to assist in lifting the machine as a whole and 55 adding to the buoyancy thereof in the air.

In the preferred embodiment of the in-

vention, the main body of the air ship comprises a central core 5 extending the full length of the machine and forming the walls of the central air passage 2 and also provided with other vertical walls 6 which divide the center frame or core into a suitable number of engine rooms 7 and passenger rooms 8. A portion of said center frame is also extended outward on each side of the machine and about centrally thereof to form 60 oppositely projecting balconies 9 from which doorways 10 lead into the rooms 8, said doorways being shown as equipped with hinged doors 11.

It will be observed that the engine room 7 is of considerable length and may be therefore used for storage purposes for carrying freight and the like. Within the central air flume or passage 2 are arranged several motors 12, 13 and 14 adapted to drive a corresponding number of propellers 15, 16 and 17, the same being mounted on shafts journaled in the opposite walls of the central passage way 2 as clearly shown in Fig. 4. The center frame is also offset as shown at 70 18 to form front and rear engine rooms 19 and 20 which may be closed off from the central air passage 2 by means of doors 21. At the front of the machine is a horizontal rudder 22 journaled on a horizontal shaft 23 and arranged partly within the air passage 2 and partly upon the outside of the body 1 of the air ship as clearly illustrated in Figs. 4 and 5, the said horizontal propeller being 75 designed to direct the machine upward or downward according to the inclination imparted to said horizontal rudder, any suitable means being employed for varying and directing the angle of said rudder. At the rear of the machine is arranged a vertical 80 rudder 24 which is journaled on a vertical axis formed by vertically alined pintles 25 received in suitable bearings in the top and bottom walls of the central air passage 2 as shown in Fig. 5. Any suitable means may 85 be employed for varying the angle of the vertical rudder 24, said rudder being designed to direct the ship to one side or the other.

By reference to Fig. 5, it will be observed 90 that the propellers 17 have arranged immediately adjacent thereto shields 26. These shields cover about one third of the upper portion of the propellers and thereby have 95 the effect of causing the propellers to direct 100 105 110

the air downward and rearward. In order to furnish an ample supply of air to the propellers, vertical air flues 27 extend through the top portion of the body and are arranged 5 to conduct air to the propellers immediately above the same as clearly illustrated in Fig. 2.

28 designates an observation room which is located below the plane of the central air 10 passage 2 and in which the operator may stand, enabling him to readily control the machine from an advantageous point.

Extending laterally and horizontally outward from the main body of the machine are 15 wings or planes 29 which it will be understood may be made of any suitable size and they may be either shaped to constitute lifting planes as shown in Figs. 2 and 3 or they may be simply used as lateral fins to aid in 20 preserving the horizontality of the body and cause the same to travel with more accuracy in a rectilinear path. The balconies 9 also serve as longitudinal side fins and assist in the same result.

25 I claim:

1. An air ship embodying a gas envelop 30 provided with a longitudinal air passage extending through the major axis thereof and open at both ends, compartments arranged in pairs at the opposite sides of the air passage and communicating therewith, air supply flues extending through the upper part of the envelop and communicating with said 35 air passage at points adjacent to said compartments, propellers located in said air passage in proximity to the flues, and propeller guards located adjacent to the junction of said air flues with the air passage and be-

tween the respective flues and adjacent compartments.

2. An air ship embodying a gas envelop 40 provided with a longitudinal air passage extending through the major axis thereof and open at both ends, central compartments arranged on opposite sides of the air passage 45 and communicating therewith, front and rear pairs of end compartments arranged on opposite sides of said passage and communicating therewith, air supply flues extending through the upper part of the envelop and 50 communicating with said air passage adjacent to the respective compartments, propellers located in said air passage in proximity to the flues and between the same and the respective compartments, propeller 55 guards in the air passage between the propeller and the compartments, and planes projecting laterally from the outer surface of the envelop.

3. An air ship embodying a gas envelop 60 provided with a longitudinal air passage extending through the major axis thereof and open at both ends, air supply flues extending 65 through the upper part of the envelop and communicating with said air passage, propellers located in said air passage in proximity to the flues, and propeller guards located adjacent to the junction of said air supply flues with the main longitudinal air passage.

In testimony whereof I affix my signature 70 in presence of two witnesses.

CLIFTON L. ANWAY.
